SPINNING RING

Louis Lichtman, New York, N. Y., assignor to
Harry Katz, New York, N. Y.

Application February 16, 1934, Serial No. 711,606

6 Claims. (Cl. 118—59)

My present invention relates to spinning rings for use on textile spinning machinery and particularly to means for lubricating the ring, whereby during a relatively long spinning operation the ring will be continuously lubricated.

In the accompanying drawing, I have shown several embodiments or forms of my present invention all adapted to the attainment of the same end, and the objects and advantages of the invention will become apparent and will be pointed out during the following detailed description of the accompanying drawing, in which

Fig. 1 is a vertical transverse sectional view through a spinning ring embodying one form of my invention, and the base or support therefor and a fragment of a frame;

Fig. 2 is an enlarged fragmentary sectional view through the spinning ring and base shown in Fig. 1;

Fig. 3 is a view similar to Fig. 2 showing another form of ring and traveler;

Fig. 4 is a view taken on the line 4—4 of Fig. 2;

Fig. 5 is a perspective view of one form of means for clamping a lubricating wick in place;

Fig. 6 is an elevation partly in section of the device shown in Fig. 5 with means for drawing the arms thereof together to grip the wick;

Fig. 7 is a perspective view similar to Fig. 5 of another form of lubricating wick; and

Fig. 8 is a view similar to Fig. 3 showing a modification in the ring, wick and clamping means therefor.

Referring to the drawing and particularly to Figs. 1, 2 and 4, the numeral 9 designates a frame on which the lateral flange 10 of the base or support for the spinning ring is mounted, said flange having upstanding clips 11 at its outer edge, and an upstanding annular flange 12 at its inner edge, the clips 11 being provided to receive the downturned edge of the lateral flange 13 of the spinning ring to connect the parts for a spinning operation.

In the form of the invention being described, the metal of which the spinning ring is formed is bent downwardly and then upwardly as at 14 to provide an inner wall 15, and then outwardly and downwardly to provide the grooved upper end 16 which is similar to the grooved end 14, and between which ends is provided an annular channel, including the grooves in said ends, around the ring to receive a wick 17 of absorbent material. The wick 17 may be formed of any suitable flexible absorbent material capable of absorbing and containing lubricating oil. At

preferably regularly spaced intervals the wall 15 is provided with openings 18. A clamping band or wire 19 may surround the wick and be drawn together at its ends either by twisting said ends around each other, or by separate means presently described, so as to draw the wick tightly against the wall 15, whereby oil may exude through the openings 18 and be drawn therethrough by the rapid rotation of the traveler T. Thus the surface of the ring which is contacted by the traveler T during its rapid rotation will at all times be lubricated, assuring smooth action and minimizing wear. Obviously, the operator or attendant may from time to time if necessary saturate the wick with more oil.

In Fig. 3 the embodiment of the invention is substantially the same as that shown in Figs. 1, 2 and 4, and the primed numerals of Fig. 3 indicate the same parts as upprimed numerals designate in Figs. 1, 2 and 4. It will be noted that in Fig. 3 instead of having the wall 15' of the ring arranged substantially in a plane vertical to the plane of the flange 13' that the metal is so bent that the wall 15' is inclined at an angle of substantially 45° or 50° to the plane of the flange 13' and instead of ring traveler T I have shown a bar traveler 21. This inclination of course arranges the grooved ends 14' and 16' also at an inclination, and consequently arranges the annular channel around the wall 15' and the wick therein at the same angle of inclination. The wick may be held in the channel by the same means disclosed in Figs. 1, 2 and 4, a simple form of which will now be described.

Referring to Fig. 5, a wire is shown in perspective provided with inwardly directed projections 22 corresponding in number and relative spacing to the number and relative spacing of the openings 18 and 18' in the walls 15 and 15' of the ring above described. The wire is bent to provide a loop 23 at its approximate center to give it a spring action. The ends of the wire may be bent outwardly as at 24 and looped as at 25, which loops may be internally screw threaded as shown in Fig. 6 to receive a screw 26 to draw the ends of the wire together and consequently force the projections 22 against the wick at the openings 18, 18' so that the wick will extend well into the openings as shown in Fig. 4, facilitating the feeding of the oil to the inner surface of the rings. It is quite obvious, and I think need not be illustrated, that the loops 25 need not necessarily be screw threaded and that a nut may be applied to the screw 26 and turned to draw the ends together. Also as above mentioned, the

loops may be omitted and the ends of the wire may be twisted about each other to draw the wire tightly against the wick to hold it in place and force portions of the wick into the openings in 5 the ring.

In Fig. 7 I have shown another type of wick embodying a wire core which may be made in several manners, such as by inserting a wire through a tubular knitted fabric or by twisting 10 the wires about strands in known manner to provide a fabric exterior surface F. Under such forms of wick it would not be necessary to provide the separate clamping wire and separate wick as in Figs. 1-4, because the wick of Fig. 7 would 15 simply be inserted in the channel between the ends 14 and 16, or 14' and 16' against the inner face of the walls 15, 15' and drawn tightly thereagainst either by threading the loops 27 on the wire core the same as in Fig. 6 or by twisting 20 the ends of the wire about each other or by means of a nut and screw as previously described. The lubrication of the wick shown in Fig. 7 would 25 be the same as in the case of the wicks described in the other figures, namely, by saturating it with oil from time to time as necessary.

In Fig. 8 I have shown still a further modification of the invention in which the ring is formed from a single blank of metal as in the other cases to provide lateral annular flange 28, corresponding 30 to the flanges 13, 13', supported by the clips 12'' which are formed as a part of the base 10''. The metal is bent downwardly from the flange 28 as at 29 and then upwardly upon itself as at 30 but is not bent outwardly and downwardly at 35 its top, the inclined ring surface 31 being rounded off at its upper end 32. Openings 33 corresponding to openings 18, 18' are provided in the wall 31 just above or at the inner end of the lateral flange 28. In connection with this type of ring, 40 I may provide a flat circular wick 34 to rest on the top of the flange 28, and the wick, if desired, may be clamped thereon by any suitable means, such as a wire or perforated metal split disc 35 having depending arms 36 which may be engaged 45 under the shoulders of the clips 12. The wick 34 should terminate or abut at its inner surface against the outer surface of the wall 31 and openings 33 of the ring. Oil could be supplied to the wick from time to time by pouring thereon or 50 by means of an oil can, so that it could escape in the manner above described through the openings 33 to the inner surface of the ring 31.

It should be apparent from the foregoing that all forms of the invention provide a ring which 55 may be preferably and easily made of a single piece of metal provided with a smooth surface on which either ring or bar travelers travel for the spinning operation, and having on its exterior a lubricating wick to supply the oil through the 60 openings and capable of being readily resaturated from time to time without stopping the spinning operation. The number of openings through which oil is fed to the inner surface is optional, and the size thereof preferably relatively small.

65 I claim:

1. A spinning ring having a lateral flange for attachment to a supporting base, an annular traveler race at the inner edge of said lateral flange,

said race having openings therethrough, a lubricating wick surrounding the outer surface of said race and overlying said openings to supply a lubricant therethrough to the inner surface of the race, and means tightly binding said wick against 5 said race, and firmly over said openings.

2. A spinning ring having a lateral extending flange for attachment to a supporting base, an annular traveler race at the inner edge of said lateral flange, said race having openings therethrough, a lubricating wick surrounding the outer surface of said race and overlying said openings to supply a lubricant therethrough to the inner surface of the race, and means holding said wick against said ring, said last means comprising a 10 band surrounding the wick and having projections 15 engaging the wick at said openings to force portions of the wick into said openings.

3. A spinning ring having an annular upstanding wall to receive a traveler, a lateral projection 20 for attachment to a supporting base, said upstanding wall being substantially C-shaped providing an annular groove around the exterior thereof, a lubricating wick in said groove, said wall having openings covered by said wick to supply a lubricant to the inner surface of said wall during a spinning operation, and means tightly binding the wick in said groove and over said 25 openings.

4. A spinning ring having an annular upstanding wall to receive a traveler, a lateral flange around said wall for attachment to a supporting base, said upstanding wall being substantially C-shaped providing an annular groove around the exterior thereof, a lubricating wick in said groove, 35 said wall having openings covered by said wick to supply a lubricant to the inner surface thereof, and a clamping band surrounding said wick and holding it in said groove firmly against the outer 40 surface of said wall over said openings.

5. A spinning ring comprising an annular wall to receive a traveler, a lateral flange around said wall for attachment to a supporting base, said wall extending above and below said flange and having openings therethrough above said flange, 45 a lubricating wick on said flange engaging the outer surface of said wall and covering said openings to supply a lubricant therethrough to the inner surface of said wall, and means for clamping said wick on said flange, said last means comprising a perforate band disposed on said wick and held thereagainst.

6. A spinning ring having an annular upstanding wall to receive a traveler, a lateral flange for attachment to a supporting base, said upstanding 55 wall being substantially C-shaped providing an annular groove around the exterior thereof, a lubricating wick in said groove, said upstanding wall having openings covered by said wick to supply a lubricant to the inner surface of said wall, and a clamping band surrounding said wick and holding it in said groove firmly against the outer 60 surface of said wall over said openings, said band having projections engaging the wick at said openings and holding portions thereof in said 65 openings.

LOUIS LICHTMAN.
